DESIGN FOR A COUNTER DECORATIVE UNIT OR THE LIKE

Harold A. Bahr, Greendale, Wis.

Application April 19, 1947, Serial No. 138,505

Term of patent 3½ years

(Cl. D29—1)

To all whom it may concern:

Be it known that I, Harold A. Bahr, a citizen of the United States, residing at Greendale, in the county of Milwaukee and State of Wisconsin, have invented a new, original, and ornamental Design for a Counter Decorative Unit or the like, of which the following is a specification, reference being had to the accompanying drawing, forming part thereof.

The figure is a view in perspective of a counter decorative unit or the like, showing my new design.

I claim:

The ornamental design for a counter decorative unit or the like, as shown.

HAROLD A. BAHR.
